UNITED STATES PATENT OFFICE.

GEORGE A. LONG, OF HARTFORD, CONNECTICUT, ASSIGNOR TO GRAY TELEPHONE PAY STATION COMPANY, OF HARTFORD, CONNECTICUT, A CORPORATION OF CONNECTICUT.

MACHINE FOR CUTTING SLOTS IN KEY BLANKS.

Application filed May 1, 1925. Serial No. 27,274.

This invention relates to a machine for cutting slots in key blanks to produce keys. The machine being of such character so as to automatically form two keys, neither of 5 which is a duplicate of another key. While the keys may with advantage be employed for a variety of purposes they are, nevertheless, usually associated with telephone pay stations, which is merely one of several uses 10 which the keys can with advantage be put. While I have a number of important objects in view, among the more vital of them is the provision in a machine of the class set forth which is accurate and positive in action and which is rapid in operation.

In the drawings accompanying and forming part of the present specifications, I have represented in detail an advantageous form of embodiment of the invention which to enable those skilled in the art to practice the same will be set forth fully in the following description:

I am not restricted to this disclosure; I may depart therefrom in a number of respects within the scope of the invention as defined by the claims succeeding such description:

Fig. 1 is a front elevation.

Fig. 2 is a side elevation as seen from the right in Fig. 1.

Fig. 3 is a top plan sectional view.

Fig. 4 is a view as seen from below in Fig. 3 of the left upper end of the machine.

Fig. 5 is a detail of a key.

Fig. 6 is a sectional detail.

Like characters refer to like parts throughout the several figures of the drawings.

The various parts of the machine may be sustained by proper frame work such as that denoted in a general way by 2.

As shown, the frame work involves a table 3, the upper side of which is reciprocative in the slide 4 which has a tongue 5 (Fig. 2).

The carrier for the keys to be cut is denoted in a general way by 6 (Figs. 1 and 2). The carrier 6 being sustained upon the upper section or plate 6^a of a series of superimposed plates mounted on the slide 4 and to partake of the necessary motion in order that the proper slotting can be obtained.

In the construction shown two key blanks are concurrently slotted as represented by Fig. 5 and it should be noted that none of the keys are the same except the two that

are simultaneously slotted; one of these two 55 being usually kept by a concern such as the telephone company and the other being delivered to a subscriber.

The base of the machine supports a standard 7 which has a bearing for rotatively 60 supporting a shaft 8 furnished at an end, the left is shown in Fig. 1 of a driver represented as a pulley 9 and driven by a belt 10 which receives its motion from an electric motor or something of a similar character. As shown the shaft 8 carries a worm 11 in a mesh with the worm gear 12 fixed to a shaft 13 and which rigidly carries the pinion 14 in mesh with the spur gear 15 which is in mesh with practically a similar 70 spur gear 16 carried by the shaft 17. Rigidly carried by the shaft 17 is a pinion 18 in mesh with a spur gear 19; the shaft of which has attached to it a cam 20 which imparts a rocking motion to a rocker 21 stepped to 75 the bearing 7^a, the rocker being oscillated by the cam 20, all as clearly shown in Figs. 1 and 2. The carrier 6 is closed into gripping engagement with the keys, or rather with the blanks thereof, by a lever as 22, Fig. 1, which 80 has a handle to facilitate the action in question. When the carrier grips the keys the carrier is advanced through the primary action of the cam 20, as will now be set forth. To the rocker 21 is pivoted a rod 23 which is 85 also connected with the shaft 24 bearing the pinion 25 in mesh with the two racks 26 and 27; the lower rack 26 being fixed, while the upper rack 27 is rigidly associated with the plates 7^a with which is operatively associated 90 the key carrier 6. When, therefore, the rocker 21 is oscillated from the position shown in said Fig. 1 to the right and is then returned the pinion 25 is advanced causing it to rotate and thus feed the rack 27 to the right 95 and then backward to the position it is shown as occupying in said Fig. 1. During one reciprocation of the rack 27 therefor two keys are concurrently slotted. Concurrently acting on the two keys during their lateral reciprocation when sustained by the carrier 6 there are concurrently acting on the blanks in the present case seven cutters as 28, as shown clearly in Figs. 1, 2, 3 and 4. The cutters are attached to spindles as 29 (Figs. 100 3 and 4) and they are in staggered relation as clearly shown in said Fig. 3 and they cut variable depths in the blank to obtain the

different slots as shown in said Fig. 2. The spindles 29 are sustained by a fixed block 30.

The spindles 29 are connected by universal joints as 31, as shown in Fig. 3, to spindles 34 which have worms 35 (Fig. 4) rigid with them and which mesh with worm gears as 36 fixed to the shaft 37 supported by a block 38. The shaft 37 has rigid with it the spur gear 39 in mesh with the pinion 40 which is rigid with a shaft 41 carrying the driven member 42 (Fig. 2 and 3) and which is connected by a belt 44 with a driver 45.

The spindles 29 extend through superimposed wedges as 46 and 47. Between the several wedges is located a bearing 48 which sustains a shaft 49 which carries upon it levers as 50 (Fig. 4), each lever being furnished with a spring operated detent 51, the detents traverse the segments as 52 (Fig. 4). Each of the levers 50 is connected by a slot and pin joint the pin being denoted by 55 and being fastened in the upper edge of the wedge 47. By the operation of a lever as 50 the depth of a cutter 29 associated therewith can be controlled.

The shaft 13 is operatively connected by gearing, denoted in a general way by 57, with a shaft 17 supported by brackets 59. The final gear has associated with it the clutch member 60. It will be assumed that the train of gears 57 is being rotated and as a consequence the clutch member 60 is also turning. The clutch member 61 will be moved into clutching engagement with the clutch member 60 by the operation of the hand lever 62, thus driving the clutching member 61. When the clutch member 61 engages the clutch member 60, the shaft 17 (Fig. 2) with which the clutch member 61 is splined is driven so that through the train of gears 63 the cam lever 20 is reciprocated to effect the reciprocation of the carrier 6.

The levers 50 are connected by pins as 49 and 55 with slides 46 and 47 thus to make easy the raising and lowering of a pair of slides and the resultant raising or lowering of a spindle 29 to regulate the depth at which a cutter is to cut into a blank.

What I claim is:

1. In a machine of the class described the combination of a plurality of spindles each having a cutter, a carrier, means to reciprocate the carrier, and means involving two slides one acting against the other to cause the spindles to cut various steps in the blank on the movement of the carrier. 50

2. In a machine of the class described the combination of a plurality of spindles each having a cutter disposed in staggered order, a carrier, and means involving two slides one acting against the other to cause the spindles to cut various steps in the blank on the movement of the carrier. 60

3. In a machine of the class described the combination of a plurality of spindles each having a cutter, duplicates of each other in staggered relation, a carrier, means for reciprocating the carrier, and means involving two slides one acting against the other to cause the spindles to cut various steps in the blank on the movement of the carrier. 65

4. In a machine of the class described the combination of a plurality of spindles each having a cutter in staggered relation with each other, a carrier, means for reciprocating the carrier, a series of levers to act against the spindles to cause them to cut slots of various depths in the key blank sustained on the carrier, and means involving two slides one acting against the other to cause the spindles to cut various steps in the blank on the movement of the carrier. 70 75 80

In testimony whereof I affix my signature.

GEORGE A. LONG.
